UNITED STATES PATENT OFFICE.

RILEY HERBERT PARKER, OF WINTHROP, AND WILLIAM E. NICKERSON, OF CAMBRIDGE, MASSACHUSETTS.

PORTABLE FIRE-EXTINGUISHING APPARATUS.

1,181,159.

Specification of Letters Patent.

Patented May 2, 1916.

Application filed September 23, 1911. Serial No. 650,940.

To all whom it may concern:

Be it known that we, RILEY HERBERT PARKER, a citizen of the United States, and a resident of Winthrop, in the county of 5 Suffolk and State of Massachusetts, and WILLIAM EMERY NICKERSON, a citizen of the United States, and a resident of Cambridge, in the county of Middlesex and State of Massachusetts, have invented certain new 10 and useful Improvements in Portable Fire-Extinguishing Apparatus, of which the following is a specification.

This invention relates to portable fire extinguishers such as are commonly located at 15 convenient points in buildings and operate when turned upside down to generate carbonic acid gas in the water with which they are filled and thereby expel the water charged with the gas through a hand nozzle 20 by means of which it may be directed upon a fire, the object of our invention being to provide a mechanism for use in connection with such an extinguisher whereby it will be caused to operate automatically and 25 discharge its contents on a fire occurring at or adjacent to the extinguisher, in case it has not been operated by hand in the usual way.

To this end we provide a mounting adapted 30 to be secured to a wall or other suitable support and to carry the extinguisher in such manner that upon the occurrence of a fire adjacent to the extinguisher a releasing device will be operated, whereupon the 35 extinguisher will automatically turn upside down and then discharge its contents through a suitable nozzle. In this connection provision may be made for holding the nozzle in suitable discharging position, and 40 the arrangement is such that the extinguisher may be released from the mounting in case it is desired to make use of the extinguisher by carrying it to a fire and then operating it as usual.

45 Various mechanisms may be employed for the purpose above described, but a simple and practical embodiment of our invention is illustrated in the accompanying drawings, in which,

50 Figure 1 is a front elevation, partly in section, showing the extinguisher in its normal or upright position; Fig. 2 is a similar view showing the back side of the extinguisher; Fig. 3 is a side elevation showing 55 the extinguisher carried in the same position by a supporting wall. Fig. 4 is a detail

view showing a supporting bearing and releasing mechanism hereinafter described; Figs. 5 and 6 are transverse sectional views showing details of the construction near the 60 top and bottom, respectively, of the frame which carries the extinguisher; and Figs. 7, 8 and 9 are front views of the extinguisher drawn on a smaller scale, and showing the same in upright position, in process of inversion, and in inverted position, respectively.

The extinguisher proper, indicated at 2 in the drawings, may be of any of the well-known types, being adapted when inverted 70 to discharge its contents through a flexible hose section 3 carrying a nozzle 4 at its extreme end. To the body portion of the extinguisher 2 is firmly secured a frame 6, which is located at the back of the extinguisher and is preferably attached thereto by means of bands 7 passing around the body of said extinguisher and connected at their ends to the frame 6 by means of bolts 8 passing through slots 9 in said frame, 80 provision being thus made for varying the position of the bands 7 somewhat in a vertical direction, in accordance with the contour of a given extinguisher. On the frame 6 there is provided, at a point slightly below 85 and preferably to one side of the center of gravity of the filled extinguisher, a rearwardly projecting hub 10 carrying a ring 11 mounted to turn on said hub on ball bearings, indicated at 12, and to the wall 13 or 90 other suitable support is firmly secured a socket member 14 having a socket 15 with a semicircular bottom adapted to receive the ring 11 but open at its top, a flange 16 being provided at the front edge of said socket to 95 hold said ring against downward or outward movement, with the hub 10 projecting forward therefrom. Above said socket is provided a releasing device preferably comprising a link of fusible solder, shown at 17, 100 which normally connects the upper end of a loose rod 18 with a hook 19 on a fixed rod 20. For convenience of illustration this rod 20 is shown as carried by the socket member 14, with the hook 19 located adjacent to the top 105 of the extinguisher, but in practice said hook 19 will be located adjacent to the ceiling of the room in which the extinguisher is placed, so that said hook will be quickly affected by the heat of a fire occurring in the room. 110 The lower end of the loose rod 18 is held in a recess formed in the top of the socket mem-

ber 14, and a pin 21, carried by the upper portion of the frame 6 and projecting rearward therefrom, occupies such a position that under normal conditions, that is, when 5 the extinguisher is supported by the socket member in upright position, said pin 21 is held between the lower portion of the loose rod 18 and an adjacent portion of the socket member 14, said rod 18 being located on that 10 side of the pin 21 toward which said pin tends to move under the influence of the forces which cause the extinguisher to invert itself when released.

As thus constructed the operation is as 15 follows: Under normal conditions the extinguisher is supported by the socket member 14 and is held in upright position by the rod 18 located in front of the pin 21, said rod being maintained in position by 20 the fusible link 17 at its upper end. While in this condition the extinguisher may readily be disengaged from its support by lifting it bodily until the ring 11 passes out 25 of the open upper end of the socket 15, whereupon the pin 21 may be withdrawn from behind the rod 18 and the extinguisher may be carried to any desired point and utilized in the usual manner. If, however, a fire occurs at a point sufficiently near 30 the link 17 to fuse the same, the upper end of the loose rod 18 will be released by the fusing of said link and the tendency of the extinguisher to invert itself, which may be produced or assisted, if desired, by means of 35 a spring 22 acting on the pin 21, will thereupon throw the upper end of said rod outward, or away from the upper portion of the socket member 14, and said rod will thereupon be disconnected entirely from said 40 socket member, leaving the extinguisher free to invert itself under the influence of gravity by turning in the ring 11, as indicated in Figs. 8 and 9. This will result, of course, in causing the contents of the extinguisher 45 to be discharged through the nozzle 4, and in order to distribute such discharge and also hold the hose 3 in suitable position during the discharge we provide a supplementary nozzle 5, which is carried by a suitable 50 bracket 23 secured to the bottom of the extinguisher and has a form of a hollow ball provided with a number of perforations radiating in practically all directions, said nozzle 5 being also provided with a hollow 55 shank of soft rubber or the like, as shown in Figs. 1 and 2, into which the end of the nozzle 4 may be inserted and in which it will be held with sufficient firmness when the extinguisher inverts itself. In case it 60 is desired to operate the extinguisher by hand, the nozzle 4 may be readily withdrawn from the soft rubber shank of the nozzle 5 and pointed in the desired direction, and

in order to prevent it from adhering to the soft rubber of the shank, it will be found 65 convenient to wrap said nozzle 4 with a piece of tissue paper (not shown).

We claim as our invention:—

1. The combination with a portable fire extinguisher of that type which is adapted 70 to discharge its contents when inverted, of a bearing carried by said extinguisher, a fixed support adapted to detachably receive said bearing, a releasing device comprising a fusible link, a pin carried by the extinguisher and normally located behind the releasing device and a spring acting on said pin in a direction to invert the extinguisher when released.

2. The combination with a portable fire 80 extinguisher of that type which is adapted to discharge its contents when inverted, of a fixed support on which the extinguisher is detachably and rotatably mounted, a pin carried by the extinguisher, a rod located 85 in front of the pin and loosely connected at one end to the fixed support, and a fusible link normally connecting the other end of said rod to said support.

3. The combination of a portable fire extinguisher of that type which is adapted to 90 discharge its contents when inverted, a flexible hose leading from the top of the extinguisher and having a discharge nozzle at its free end, a fixed support and means for 95 detachably and rotatably mounting the extinguisher thereon, means comprising a heat-operated releasing device for normally holding the extinguisher in upright position, and a supplementary discharge nozzle carried 100 by the lower portion of the extinguisher and having means for detachably receiving the discharge nozzle carried by the hose.

4. The combination of a portable fire extinguisher of that type which is adapted to 105 discharge its contents when inverted, a flexible hose carried thereby and having a discharge nozzle, a fixed support and means for detachably and rotatably mounting the extinguisher thereon, means comprising a 110 heat-operated releasing device for normally holding the extinguisher in upright position, and a supplementary nozzle carried by the extinguisher and having a hollow rubber shank adapted to detachably receive the 115 end of the discharge nozzle carried by the hose.

In testimony whereof, we have hereunto subscribed our names this 21st day of September, 1911.

R. HERBERT PARKER.
